ATTORNEY

UNITED STATES PATENT OFFICE.

ISAIAH WASHINGTON BENNETT, OF NEW YORK, N. Y., ASSIGNOR TO HIMSELF AND JAY LIVINGSTON BENNETT, OF NEW YORK, N. Y.

HAND-PROPELLED VEHICLE.

1,319,321.

Specification of Letters Patent.

Patented Oct. 21, 1919.

Application filed March 30, 1918. Serial No. 225,652.

To all whom it may concern:

Be it known that I, ISAIAH WASHINGTON BENNETT, a citizen of the United States, and resident of the borough of Bronx, 5 county of Bronx, city and State of New York, have invented certain new and useful Improvements in Hand-Propelled Vehicles, of which the following is a specification.

The device the subject of this invention 10 may be considered as a toy, for it is my intention that it shall be constructed of comparatively small size, for the use of children.

In the drawings I have shown two different 15 constructions, or rather, two constructions which differ only to the extent of the mechanical workmanship, and it is my intention to produce this device in this manner so that it may be extremely unmechanical 20 for smaller children, and more mechanical and interesting for larger children.

Much importance is attached to the shape and to the means for operating my device, as it is my desire to give this toy all of the 25 attractiveness of an automobile, and yet, to make it self-propelled, cheap, and simple in operation.

The following is what I consider a good 30 means of carrying out my invention, and the accompanying drawings should be considered for a complete understanding of the specification which follows:

In the drawings:—

Figure 1 shows a side elevation of a device 35 of simple construction.

Fig. 2 a side elevation of a more mechanically perfect device.

Fig. 3 shows a top plan view of the construction shown in Fig. 2, and

Fig. 4 is a reverse plan view of it, and 40 may be considered as showing the mechanism of the device shown in Figs. 1 and 2.

Similar reference numerals indicate like 45 parts in all the figures where they appear.

In describing my invention, I will first set forth the construction of the device shown in Fig. 1.

In this figure, I provide a supporting 50 member 1 which may be a plank or board of wood, of suitable width and length, and secured to this plank 1, is a seat 2, the forward portion of which is rounded. The seat is provided with a back 3 and it is obvious that the seat and back must both be sup-

ported in a manner to assure sufficient 55 strength and rigidity.

Back of the member 3 is a box portion 4 also constructed of wood, but having no general utility.

The front end of my device is provided 60 with what may be termed a bonnet 5 extending from the extreme front end rearward to the point 6. The member 5 is of a width equal to that of the plank 1, and the edges of the member 5 may be rounded if 65 desired.

Extending rearward from the point 6 is a cabinet 7 narrower than the adjacent portion of the bonnet 5, and in this cabinet 7 I arrange suitable bearings for the support 70 of a crank shaft 8 and on the crank shaft 8 is a sprocket 9 driving a chain 10 which chain extends over a sprocket 11, on a shaft 12 supported in bearing blocks 13 under the plank 1. 75

The ends of the crank shaft 8 extend through a chamber or cabinet 7 and these ends are provided with cranks 14 only one of which is shown in Fig. 1, and a grip or handle 15 completes the crank 14. 80

Upon the shaft 12 is a second gear or sprocket 16, and a chain 17 extends rearwardly passing over the sprocket upon the rear axle 18. The rear wheels 19 are secured to the axle 18, and it is obvious that pillow blocks or other suitable means are provided for rotatably supporting the axle 18. 85

The front wheels 20 are received and rotatably supported upon the axle 21, and this axle is pivoted at mid-length by king bolts 90 in the manner found in horse-drawn vehicles.

A centrally pivoted bar 22 is arranged adjacent to the seat 2 and within easy reach of the feet of the operator. This bar extends outward at each side of the plank 1 and is connected to the front axle 21 by means of rods 23 and therefore, when either end of the bar 22 is pressed, the axle 21 will be turned to a degree corresponding 95 with the pressure applied to the bar 22, and as the bar 22 may be turned in either direction, the front wheels may be turned to steer the device.

The propulsion of this vehicle is accomplished by turning the crank 14 which will 100 revolve the sprocket 9 and through the chain 10 the sprockets 11 and 16 will also be ro-

tated. The chain 17 passing over a sprocket secured to the back axle will turn the wheels 19 and move the vehicle forward or backward according as the crank 14 is moved.

5 In Fig. 2, I show a device of somewhat more complicated construction, complicated, however, only to the extent of a more mechanically complete device. In this figure, what may be considered the frame or body, 10 as shown at 30 is constructed of angle iron. The bonnet 31 has a cover 32, hinged at 33, and this cover may be lifted. The forward portion of the bonnet or that portion under the cover 32 may be used for carrying tools 15 or other devices.

The reduced portion or cabinet 34 containing the sprocket 35 and the bearings for the crank shaft 36 may also be provided with a cover 37 which may be raised, so that 20 the crank shaft bearings and contents may be lubricated. The crank 38 and handles 39 may be of improved shape or design, but the function is similar to that crank 14 shown in Fig. 1.

25 The shaft 40 is received in bearing blocks 41 and 42 secured to the frame members 30 and upon the shaft 40 are sprockets 44 and 45. The chain 46 extending downward from the sprocket 35 passes over the sprocket 45 and a chain 47 from the sprocket 44 passes over a sprocket 48 secured upon the rear axle 49. The rear axle 49 is rotatable, and secured one at each end of the axle are wheels 50 and 51. Bearing blocks 52 and 35 53 support the rear axle 49.

The wheels shown in Fig. 2 and similar figures are wire wheels provided with rubber tires 54 and an extra wheel 55 is mounted upon the rearmost cabinet 56 and 40 this cabinet 56 may be provided with a cover 57 hinged at 58.

The seat 59 and the back portion 60 are each cushioned in this device, and the body, 45 wheels, and other portions may be made as decorative as desired.

The front wheels 61 and 62 are rotatably mounted upon projections from a bar 63. The bar 63 is pivoted at 64 to any suitable portion of the frame and rods 65 and 66 50 extend from studs 67 and 68 in the bar 63 and are engaged with a centrally pivoted

member 69 adjacent to the seat of the operator. This member 69 may be a straight bar or may be formed of spring steel, or other suitable material, as indicated in the drawing.

It is obvious that the location of the steering bar 69 of the sprockets and cranks and of other parts may be changed at will, that the size of the device may be varied, but I 60 prefer the whole constructed generally as shown and described.

The wheels of the device shown in Fig. 1 may be disked wheels or spoked wheels.

The device shown in Fig. 1 may be constructed entirely of wood with the exception of the crank shaft 8, the shaft 12, and the sprockets and chains. It is obvious that the spare wheel 55 shown in Fig. 2 may be omitted.

Having carefully and fully described my invention, what I claim and desire to secure by Letters Patent is:

A manually propelled vehicle having 75 an elongated frame, wheels upon which said frame is mounted, a seat arranged upon said frame toward the rear thereof, a bonnet mounted upon said frame and being of equal width to the frame throughout the main portion of its length, the rear portion of said bonnet being of diminished width and in close proximity to the said seat, a transversed shaft journaled in the said rear portion of the bonnet, an operative connection between said shaft and the rear wheels, 80 crank arms secured to said shaft, handles upon outer ends of said crank arms, said handles being wholly within the vertical confines of the said frame, a steering bar centrally pivoted at a point where the 85 bonnet is diminished in width, the ends of said steering bar projecting beyond the vertical confines of the said frame and a connection between said steering bar and the front wheels of the vehicle.

90 Signed at New York city, in the county and State of New York, this 9 day of March, 1918.

ISAIAH WASHINGTON BENNETT.

Witness:

ARTHUR E. DINKE.

Copies of this patent may be obtained for five cents each, by addressing the "Commissioner of Patents Washington, D. C."
